UNITED STATES PATENT OFFICE.

HUBBARD T. BUCKNER, OF SEATTLE, WASHINGTON.

SURGICAL SPLINT.

1,243,137.

Specification of Letters Patent. Patented Oct. 16, 1917.

Application filed June 2, 1917. Serial No. 172,547.

To all whom it may concern:

Be it known that I, HUBBARD T. BUCKNER, citizen of the United States, residing at Seattle, in the county of King and State of Washington, have invented a certain new and useful Improvement in Surgical Splints, of which the following is a specification.

My invention relates to improvements in surgical splints, and the object of my invention is to provide a splint which shall embody adjustable parts that may be moved to dispose them in different relative positions, as may be required in different surgical cases, to adapt said splint rigidly to maintain in required positions the different portions of the injured one of the two arms of a person.

I accomplish this object by devices illustrated in the accompanying drawings, wherein—

Figure 1 is a perspective view of a splint embodying my invention;

Fig. 2 is a view of the same in side elevation;

Fig. 3 is a view of the same in vertical section on broken line 3, 3 of Fig. 2; and

Fig. 4 is an enlarged fragmentary plan view of parts of the same.

Referring to the drawings, throughout which like reference numerals indicate like parts, a frame made of a thin bar of metal is formed to have side members 5 and 6 which diverge from a semi-circular portion 7, the side member 5 being longer than the side member 6 and its free end portion 8 being curved in a sidewise direction toward the plane of the side member 6 to terminate at a point distant from the free end of said side member 6, as more clearly shown in Fig. 1.

The curved portion 8 of the side member 5 is provided with a slot 9 that extends lengthwise thereof from a point near its free end to a point near the straight portion of said side member 5, through which slot 9 is disposed to extend the shank of a clamping screw 10 that is adapted to be slidably and adjustably moved to any desired position between the ends of said slot 9.

Rigidly fastened to the inner end portion of the clamping screw 10 is the base end portion of a bracket 11 which is provided with a rigidly attached guiding member 12 that slidably engages with the side edges of the curved portion 8, while the outer end portion of the clamping screw 10 is provided

with a clamping wing-nut 13 which may serve in an obvious manner releasably to fasten the base end portion of the bracket 11 against the inner side surface of the curved portion 8 at any desired point to which it may be moved.

The bracket 11 is formed to extend from its base portion toward the semi-circular portion 7 for a short distance, thence at a right angle for a longer distance through and beyond the plane of the side member 6 at a point spaced from the free end of said side member 6, as shown more clearly in Fig. 1.

Articulated to the free end of the side member 6 is one end of an arm 14 that is adapted to be swung to and from a normal position where it is spaced from and parallel with the oppositely disposed longer portion 70 of the bracket 11.

A member 15 is made of a rectangular piece of sheet metal bent into the form of a semi-circle and having its opposite circular edge portions 16 flared outwardly and having its opposite straight edge portions 17 each reinforced by a metal bar 18 that is rigidly fastened to the outer side surface thereof.

The member 15 is further reinforced by two metal straps 19 riveted thereto and disposed to extend around the exterior surface thereof from the outer side surface of one of the bars 18 to the outer side surface of the other of said bars 18 each adjacent to a different one of the outwardly flared circular edge portions 16.

Fixed in the central portion of each of the bars 18 to extend directly outward therefrom is a screw-threaded stud 20, and fixed in each of the opposite end portions of each of said bars 18 to extend through the adjacent end portion of the adjacent strap 19 is a dowel pin 21.

The member 15 is removably disposed between the arm 14 and the bracket 11 where it is releasably and rigidly fastened by means of the dowel pins 21 and the screw-threaded studs 20 which project through holes provided in said arm 14 and in said bracket 11, 100 the screw-threaded studs 20 being provided with wing-nuts 22 which are adapted to engage with the outer sides respectively of the arm 14 and bracket 11.

The member 15, with respect to the arm 14, 110 the bracket 11 and the frame, may be quickly changed from its position shown by full lines

in Fig. 2 to the inverted position indicated by dotted lines 23 in said Fig. 2 when it is desired to apply the splint to the left arm of a person, said change being effected by removing the nuts 22 and swinging the arm 14 away from the member 15 and disengaging said member 15 from the bracket 11, and thereupon inverting said member 15 and disposing it in the reverse position between the arm 14 and bracket 11 and in an obvious manner replacing the wing-nuts 22.

Articulated to the side members 5 and 6 to extend in a semi-circle therebetween are two metal straps 24 and 25, respectively, both 15 of which are adapted to be changed from their positions shown by full lines in Fig. 2 to the positions indicated respectively by dotted lines 26 and 27 in said Fig. 2.

The two straps 24 and 25 are made of thin 20 springy metal to adapt them to yield when the diverging side members 5 and 6 are moved toward each other or away from each other in response to changes in the position of the bracket 11 with respect to the curved 25 portion 8, which changes may be made to adapt the splint better to fit an arm of any particular size.

Manifestly, the parts of the splint illustrated by full lines in the drawings are disposed to adapt the splint to be applied to the 30 right arm of a patient, but inverting or reversing the positions of the member 15 and the straps 24 and 25 to cause them to assume the respective positions indicated by the dotted lines 23, 26 and 27 of Fig. 2 will adapt 35 the splint to be applied to the left arm of a patient.

In applying the splint to a patient's arm, the arm is properly bandaged and disposed 40 with the fore arm and hand extending between the side members 5 and 6 from a point near the semi-circular portion 7 to a point that will permit that portion of the arm just above the elbow to be disposed within 45 the member 15 when the arm is bent approxi-

mately to a right angle, and when the arm is so disposed, the bracket 11 is moved on the curved portion 8 to be fastened at a position best adapted to cause the splint snugly to fit the contour of the arm, and thereupon 50 the now rigid splint is securely lashed to the bandaged arm by a tape or suitable cord disposed to maintain the different portions of the arm in their desired relative positions.

Obviously, changes may be made in the 55 form, dimensions and arrangement of parts of my invention without departing from the spirit thereof.

What I claim is:

A splint of the class described which 60 embodies a frame member formed of a single metal bar that is bent at one portion of its length to form a semi-circular portion from which extend two diverging side members of different lengths, the free end portion of 65 the longer side member being bent to extend through the plane of the shorter side member at a point spaced from the free end of said shorter member; a plurality of flexibly yielding metal straps pivotally attached to 70 said side members each to extend in a semi-circle therebetween; an angular bracket adjustably clamped to the inner side of said free end portion of said longer side member, one portion of said angular bracket being disposed to extend through and beyond the plane of said shorter side member at a point spaced from the end of said shorter side member; an arm having one of its ends 75 pivotally attached to the free end of said shorter side member and adapted to be swung to and from a plane parallel with and spaced from the plane of said one portion of said angular bracket; and a semi-circular sheet metal member releasably clamped to 80 said pivotally attached arm and to said bracket to extend therebetween.

In witness whereof, I heretunto subscribe my name this 26th day of May, A. D. 1917.

HUBBARD T. BUCKNER.
